ELECTRIC PICKUP FOR PHONOGRAPH RECORDS

Application filed May 19, 1928. Serial No. 278,989.

This invention relates to an electrical pickup device for use in connection with phonograph records, and is adapted to be used in place of the ordinary reproducer comprising a part of the phonograph.

In the use of an electrical pickup device of the character herein described, the generating coil, within which an electric current is set up by changes of magnetic flux through the coil due to movement of an armature structure, is connected to the primary of a step-up transformer, the secondary of which is connected to the grid of an amplifying tube in an amplified set, such as is ordinarily used in connection with radio circuits, and in consideration of the device herein described, this sort of a system should be considered as being used in connection with the device of this application.

It is therefore the object of my invention to provide an electrical pickup for phonograph records which is highly efficient in translating the mechanical sound record into an electrical current having undulations corresponding to the sound impressions on the record.

Another object of my invention is to provide an electrical pickup for the purpose described, in which the construction is such as to eliminate all adjustments after the device has once been assembled.

Another object of my invention is to provide a device of the character described which is relatively light and which will therefore not cause the needle to cut the records.

Another object of my invention is to provide an electrical pickup which is easy to make and assemble, and hence, cheap to manufacture.

These and other objects will be apparent to one skilled in this art, after a study of the specification taken in connection with the annexed drawing, wherein:

Figure 1 is a side elevation of the electrical pickup device with the set screw for clamping the needle, removed.

Figure 2 is a side view of the device as shown in Figure 1, but with the needle set screw in position.

Figure 3 is a view looking at the bottom of the device.

Figure 4 is a top plan view of the device, but with the magnet removed.

Figure 5 is a perspective view of the unitary movable armature structure.

The figures illustrating the device, are substantially twice the size of a satisfactory working device.

Referring now to the details, wherein like numbers refer to corresponding parts in the various views,

1 is a base of non-magnetic material such as brass, on which are mounted pole pieces 2 and 3 of suitable magnetic material. These pole pieces may be fastened to the base 1 in any satisfactory manner, as by pins 4—two for each pole piece, which preferably are of magnetic material and also act to bring a certain amount of magnetic flux down to the vicinity of the end of the coil core to be hereinafter referred to. It is preferable to keep the reluctance of the magnetic circuit at this point relatively high. The pole pieces 2 and 3 are bent over at one end and tapered as indicated by the numeral 5, these tapering ends extending toward each other, and pass over one end of a generating coil 6, which is thus positioned between the pole pieces 2 and 3, and between the base 1 and the tapered end 5.

Positioned on the upper side of the base 1 and in contact with the pole pieces 2 and 3, is a magnet 7 which is the last thing to be assembled on the device. The bottom side of the base 1 is provided with a recess 13, and positioned within this recess, is a movable structure, comprising a damping plate 8 of suitable material, preferably of aluminum, to give lightness, which as illustrated is rectangular in shape and to which is attached a stem 9, which projects upwardly through the coil 6, thereby forming a magnetic core for the coil, and downwardly through the socket 19. The free end of the core stem 9 is preferably flattened at 10 for cooperation between the tapered ends 5 and the pole pieces 2 and 3. The dampener 8 is resiliently mounted within the recess 13 by means of very flexible members 11 and 12. I have secured excel-

lent results by making the members 11 and 12 out of soft rubber, and these soft rubber pieces are at least somewhat longer and preferably wider than the corresponding dimensions of the member 8. The pieces 11 and 12 may be made so as to completely envelop the plate 8. The base 1 need not have a recess 13 as described, but I prefer this arrangement.

These dampener mounting pieces 11 and 12, together with the plate 8, are held in place within the recess 13 by a clamping strip 14, having ears 15 and 16 through which screws 17 and 18 pass, and the plate 8 may be set in proper adjustment by means of these screws. The plate 8 is provided with a socket 19 through which the lower end of the core stem 9 extends, and this end has a hole 20 therein to receive a record-playing needle which is clamped into position by a set screw 21. In some cases, a rubber cap may enclose the tapered ends of the pole pieces without coming into contact with the end 10 of the core, to keep foreign material from getting into the air gap at this place.

By reason of the construction as above illustrated and described, I have obtained an electrical pickup which is especially effective in obtaining the objects of the invention previously set forth, and I have found that the device is especially effective in reproducing records of the "hill and dale" type but of course is not limited only to use in connection with records having this characteristic.

The operation of my device is comparatively simple and readily understood. As the needle which is fastened to the socket 19 follows the record, it moves the plate 8, and at the same time shifts the core stem 9 alternately to and from one pole piece to the other, thereby changing the amount and direction of the magnetic flux through the coil 6, and setting up an electrical current in the coil, which current is amplified in the manner heretofore explained.

Having thus described my invention, what I claim is:

1. In a device of the class described, a base, a magnet positioned on the base, a generating coil disposed on the base between the limbs of the magnet, a pair of pole pieces for the magnet having free ends tapered and extending toward each other over the end of said coil which is farthest from the base, said base having a recess therein, a plate movably mounted within said recess and having a stem projecting through the coil forming a core thereof and terminating between the tapered ends of said pole pieces, and a socket member attached to the plate and adapted to receive a record-playing needle.

2. In a device of the class described, a base, a magnet positioned on the base, a generating coil disposed on the base between the

limbs of the magnet, a pair of pole pieces for the magnet having free ends extending over the end of said coil which is farthest from the base and turned toward its axial center, said base having a recess; a plate positioned in said recess between two pieces of flexible material and having a stem extending between said pole pieces, a clamp for holding the plate and said pieces of flexible material within the recess, and a socket member attached to the plate and adapted to receive a record-playing needle.

3. In a device of the class described, a base, a magnet positioned on the base, a generating coil disposed on the base between the limbs of the magnet, a pair of pole pieces for the magnet having free ends extending over the end of said coil which is farthest from the base and turned toward its axial center, said base having a recess; a plate positioned in said recess between two pieces of soft rubber having a length and breadth at least as great as the corresponding dimensions of the plate, said plate having a stem extending between said pole pieces, a clamp for holding the plate and said pieces of flexible material within the recess, and a socket member attached to the stem and adapted to receive a record-playing needle.

4. In a device of the class described, a base, a magnet positioned on the base, a generating coil disposed on the base between the limbs of the magnet, a pair of pole pieces for the magnet having free ends extending over the end of said coil which is farthest from the base and turned toward its axial center, a pair of pieces of flexible material, a plate positioned between said pair of pieces and substantially enclosed thereby and having a stem forming a core for said coil and having its extremity positioned between said pair of pole pieces, a clamp extending over said plate and resting against one of said pieces for adjustably mounting the said two pieces and plate to the base and a socket member attached to the plate and adapted to receive a record-playing needle.

5. In a device of the class described, a magnet, a generating coil, pole pieces extending from the opposite limbs of the magnet over at least one end of the coil and terminating on opposite sides of the axial center of the coil so as to form an air gap at one end of the coil, a support member, a movable structure comprising a plate positioned adjacent the opposite end of the coil and having a stem of magnetic material projecting through the coil and into said air gap, a flexible piece of material on opposite sides of the plate and covering the entire sides and between which the plate may oscillate, a clamp extending over said plate and resting against one of said pieces for holding the plate and pieces of flexible material to the support and means

for attaching a needle to the movable structure.

6. In a device of the class described, a magnet, a support member therefor, a generating coil carried by the support, pole pieces extending from the opposite limbs of the magnet over the end of the coil away from the support and terminating on opposite sides of the axial center of the coil so as to form an air gap, a plate positioned adjacent the opposite end of the coil and having a stem projecting through the coil and into said air gap, means for flexibly mounting the plate to the support comprising two thin pieces of soft rubber, one on each side of the plate and covering the entire side and extending beyond the plate at least on two sides whereby the plate may oscillate between the said rubber pieces as pivots, a clamp extending over said plate and resting against one of said pieces for holding the plate and rubber pieces to the support, and a needle socket carried by the stem.

In testimony whereof I affix my signature.
